CLAIM

The ornamental design for an antenna used in wireless communication, as shown and described.

DESCRIPTION

FIG. 1 is a perspective view of an antenna used in wireless communication showing my new design;
 FIG. 2 is a front elevational view thereof;
 FIG. 3 is rear elevational view thereof;
 FIG. 4 is a left side elevational view thereof;
 FIG. 5 is a right side elevational view thereof;
 FIG. 6 is a top plan view thereof; and,
 FIG. 7 a bottom plan view thereof.
